COIN RECEPTACLE

Edward C. Arzig, Chicago, Ill., assignor to Miller Meters, Inc., a corporation of Illinois

Application July 29, 1954, Serial No. 446,581

4 Claims. (Cl. 232—15)

The present invention relates to a coin receptacle and more particularly to a coin receptacle adapted for use with a coin operated mechanism such as a parking meter or the like.

It is the general object of this invention to produce a new and improved coin receptacle.

It is a more specific object of the invention to produce a coin receptacle adapted for use within the housing of a parking meter or the like and which is automatically opened and closed as the closure door for the housing is opened and closed.

It is another object of the invention to produce a coin receptacle of the type described in the preceding paragraph to provide for rapid emptying of the receptacle by a collector and thus the coin receptacle of the present invention is opened by movement of the housing closure to open position, thereby dumping the coins in the receptacle into a suitable bag or other depository carried by the collector and further to provide a coin receptacle which not only is automatically closed as the closure for the housing is closed, but also one which will prevent the closure from being fully closed unless the coin receptacle is also fully closed. By reason of the foregoing construction, reliance need not be placed on the operation of other receptacle closing means which may or may not function as the housing is closed and whose malfunction can be asserted only by the coin receptacle's failure to retain coins therein.

A further object of the invention is to provide a coin receptacle of the type disclosed in the preceding paragraphs which is provided with a coin slot to be aligned with a coin discharge passage leading from the coin operated mechanism which coin slot is normally closed by spring members but is opened as the coin receptacle is moved to coin-receiving position, thereby permitting coins passing through the passage to drop into the coin receptacle.

Other and further objects and advantages of the invention will be readily apparent from the following description and drawings in which—

Fig. 1 is a side elevational view of a parking meter with which the present invention may be used;

Fig. 2 is a front elevational view of the parking meter shown in Fig. 1;

Fig. 3 is an enlarged vertical sectional view of the lower portion of the housing shown in Figs. 1 and 2;

Fig. 4 is a vertical sectional view taken 90° from the section of Fig. 3;

Fig. 5 is a vertical sectional view of the lower portion of the parking meter shown in Fig. 1 showing the closure door in partially opened position;

Fig. 6 is a view like Fig. 5 showing the closure in fully opened position;

Fig. 7 is a view like Fig. 5 showing the closure moved partially toward closed position;

Fig. 8 is a vertical sectional view of the top portion of the coin receptacle of the present invention;

Fig. 9 is a top plan view of said coin receptacle;

2

Fig. 10 is a vertical sectional view showing the top portion of the receptacle of the present invention and a portion of the parking meter housing; and

Fig. 11 is a fragmentary sectional view along line 5 11—11 of Fig. 3.

While this invention is susceptible of embodiments in many different forms, there is shown in the drawings and will herein be described in detail one specific embodiment, with the understanding that the present disclosure is to be considered as an exemplification of the principles of the invention and is not intended to limit the invention to the embodiment illustrated. The scope of the invention will be pointed out in the appended claims.

For the purpose of exemplary disclosure the present invention has been illustrated and will hereafter be described as used in conjunction with a parking meter, although it will be clear to those skilled in the art that the principle of the invention may be embodied in other forms and that the coin receptacle herein described and 10 claimed may be used in conjunction with other coin operated devices.

Referring now to the drawings, there is shown a parking meter generally designated as 20, having a housing divided by a horizontal plate 21 into an upper portion 22 enclosing the mechanism of the parking meter and a lower portion 23 into which coins inserted in the meter are ultimately discharged. The parking meter 20 is mounted on a post 24 in the usual manner.

The lower portion 23 of the housing is provided with 15 a closure door 25 which is hinged at 26 to the housing and provided with a lock 27. Mounted on the closure is a substantially rectangular container 28 having one side thereof made in the form of a sliding door 29. To provide for sliding movement of the door 29, it is provided 20 with flanges 30 (Fig. 11) slideable in channels 31 formed on opposite side walls of the container 28. The door is provided at one end with an inturned edge 32 and intermediate its ends with a lip 33 for purposes hereafter to be described.

25 A leaf spring 35 is secured to a side 36 of the lower housing portion 23 and is provided with a hook-like end portion 37 extending into the path of movement of the door 29 and more specifically into the path of movement of the lip 33 as the closure is moved from the position shown in Fig. 5 to the position shown in Fig. 6.

The plate 21 is provided with a coin passage 38 through which coins inserted in the meter ultimately pass, and the coin receptacle 28 is provided with a slot 39 on its top face aligned with the passage 38 when the receptacle is in the coin-receiving position illustrated in 30 Figs. 3, 4 and 10. Adjacent the coin slot 39 there is mounted a pair of spring members 40 normally urged to the positions shown in Figs. 8 and 9 closing or blocking off the slot 39. On the bottom of the plate 21 is 35 formed a plurality of lips 41 positioned to contact portions of the spring members 40 as the coin receptacle is moved to coin-receiving position, thus bending the spring members 40 inwardly as illustrated in Fig. 10, thereby opening or unblocking the slot 39 to permit coins to drop into the receptacle.

40 The operation of the coin receptacle of the present invention will readily be understood from the foregoing description and by a reference to Figs. 5—7. When the lock 27 is opened and the closure 25 swung upwardly, the receptacle, being mounted on the closure, moves therewith. As the hook portion 37 is positioned in the path of movement of the lip 33, as the closure is swung outwardly, engagement of the lip by the hook portion 37 occurs and further outward swinging movement of the closure serves to slide open the door 29 permitting the coins to fall out. Thus when the coin receptacle is in the position of Fig. 6, it is in a coin-discharging position.

A collector collecting coins from the parking meters need only position his coin bag adjacent the face of the meter, insert the key in the lock and swing the closure 25 outwardly. The coin receptacle will thereupon automatically be opened in the manner just described and the coins therein discharged.

After the coins have been discharged, the collector need merely close the closure 25 and, by virtue of the fact that a complete closure can be effected, he is assured that the coin receptacle has also been closed. It will be noted in Fig. 7 that as the closure 25 is being closed, that is, is being moved in the direction of the arrow, the inturned edge 32 of the door contacts the lower face of the horizontal plate 21 and further closing movement of the closure serves to slide the door 29 to closed position on the receptacle. As the coin receptacle is moved to coin-receiving position, not only is the door 29 fully closed, but also the lips 41 will have contacted the spring members 40 opening the slot 39. Should for any reason the door 29 jam or otherwise fail to close, such malfunction is made clear to the collector, as he will be unable to effect complete closing of the closure 25 and thus receive a warning of the fact that the coin receptacle is not operating properly.

From the foregoing it is believed clear that the coin receptacle of the present invention is such as to provide a speedy emptying of the coins from the receptacle by merely opening the housing closure door, that the door of the coin receptacle is automatically closed as the closure is shut and that a warning is provided for the collector in the event the coin receptacle door should fail to operate properly. Thus the collection of coins from the coin receptacles can not only be speedy, but also can be effected with full assurance that upon shutting of the closure, the coin receptacle is again properly conditioned to receive further coins from the meter.

I claim:

1. A coin receptacle for use in a parking meter housing or the like comprising a container mounted in the housing for movement between a coin-receiving and a coin-discharging position, a sliding door on the container having a portion engageable with means for opening the door, door opening means in the housing and extending into the path of movement of said engageable portion on the door, said door opening means being spaced from the engageable portion when the container is in the coin-receiving position and being operable to engage said engageable portion and open the door only after the container has been moved a predetermined distance toward coin-discharging position, and other means in the housing positioned to engage and close the door as the container is moved to coin-receiving position.

2. A coin receptacle for use in a parking meter housing or the like having a movable closure for the housing comprising a container mounted on the closure and within the housing and movable with movement of the closure from a coin-receiving to a coin-discharging position, a sliding door on the container having a portion engage-

able with means for opening the door, door opening means in the housing and extending into the path of movement of said engageable portion on the door, said door opening means being spaced from the engageable portion when the container is in the coin-receiving position and being operable to engage said engageable portion and slide open the door only after the container has been moved a predetermined distance toward coin-discharging position, and means in the housing positioned to engage and close the door as the container is moved to coin-receiving position, with the last named means and said door cooperating to prevent movement of the closure to move the container to coin-receiving position until said door is closed.

3. A coin receptacle for use in a parking meter housing or the like having a swingable closure for the housing comprising a container mounted on the closure and swingable therewith from a coin-receiving to a coin-discharging position, a sliding door on the container, a door opening member in the housing having a hook-like portion positioned in the path of movement of a part of the door, being spaced from said part when the container is in the coin-receiving position, and being operable to engage said part and slide open the door only after the container has been moved a predetermined distance toward coin-discharging position, said housing having a portion positioned to engage and slide closed the door as the container is moved to coin-receiving position with said portion of the housing and said door cooperating to prevent movement of the closure to move the container to coin-receiving position until said door is closed.

4. A coin receptacle for use in a parking meter housing or the like having a pivoted closure for the housing comprising a container mounted on the closure and pivotable therewith from a coin-receiving position wherein in a slot in the container is aligned with a coin passage in the housing to a coin-discharging position, a sliding door on the container having an engaging portion, a leaf spring secured to the housing and having a hook-like portion positioned in the path of said engaging portion on movement of the door, said hook-like portion being spaced from said engaging portion when the container is in the coin-receiving position and operable to engage said engaging portion and slide open the door only after the container has been moved a predetermined distance toward coin-discharging position, and said housing having a portion positioned to engage and slide closed the door as the container is moved to coin-receiving position with said portion of the housing and said door cooperating to prevent movement of the closure to move the container to coin-receiving position until said door is closed.
